UNITED STATES PATENT OFFICE.

PETER POWERS, OF CARLISLE, NEBRASKA.

BUNDLE-SUPPORTER FOR THRESHERS.

1,103,312.

Specification of Letters Patent.

Patented July 14, 1914.

Application filed October 28, 1913. Serial No. 797,815.

To all whom it may concern:

Be it known that I, PETER POWERS, a citizen of the United States, and a resident of Carlisle, in the county of Fillmore and State 5 of Nebraska, have invented a new and Improved Bundle-Supporter for Threshers, of which the following is a full, clear, and exact description.

My invention relates to self-feeders of 10 threshing machines, and particularly to an attachment adapted to be applied to self-feeders of known make whereby to support the bundles at the outer end of the self-feeder, and provided with means for adjusting the width of the attachment to suit 15 different self-feeders.

The invention includes a novel manner of supporting the divide board, whereby it can be raised or lowered by the attendant without 20 the assistance of an extra man.

It is also a design of my invention to provide a device of the indicated character, constructed to promote efficiency in operation, as well as economy of manufacture, and 25 adapted to be readily secured in position.

The invention will be particularly explained in the specific description following.

Reference is to be had to the accompanying drawings forming a part of this specification, in which similar characters of reference indicate corresponding parts in all 30 the views.

Figure 1 is a longitudinal sectional view of my improved attachment, showing the 35 same applied to the self-feeder of a thresher; Fig. 2 is a plan view on a larger scale; Fig. 3 is a detail vertical section on the line 3—3, Fig. 2; Fig. 4 is a detail transverse section on line 4—4, Fig. 2; and Fig. 40 5 is a separate perspective view of the bundle supporter.

My improved attachment is applicable to the self-feeder 10, and is securable to the outer end thereof to range across the latter 45 and inclose the same. The particular self-feeder illustrated is provided with a cross-stick 11, on which the supporting legs (not shown) are secured; my attachment, designated usually by the numeral 12, is, in the 50 illustrated form, secured at the bottom to the said cross-stick. The front 13 of the attachment, in the present instance, is secured by bolts 14 to the cross-stick. At the top the attachment is flared outwardly, as at 55 15, to support the bundles, and the ends are returned as at 15^a. The corners of the flar-

ing upper end may have filled angle pieces 15^d. At the forward edges the attachment is fastened to the self-feeder 10 and may be provided for the purpose with bolt holes 60 15^b, to receive bolts or rivets 15^c.

The divide board 16 of the self-feeder in my invention is supported in a novel manner, the outer end being received in a central opening 17 formed in the front 13 and flared top 15 of the attachment. Near the outer end the divide board rests on a bearing plate 18, which is formed by bending downward a tongue resulting from the forming of the opening 70 17. The attachment 12 is formed in sections 18 slidable on each other and united by bolts 19 received in bolt holes 20 which permit of the width of the attachment being varied. The upper end of the attachment is return 75 bent forming an inclined member 12^a that terminates above and adjacent to the upper stretch of the bundle-carrying belt 22. For additional strength a strap 21 of metal is secured at its ends respectively to the attachment 12, at the ends of the latter, and to the adjacent side portions of the self 80 feeder 10.

The divide board 16 at its inner end is hung by a link 23 from the top 10^c of the self feeder in the construction shown, and to the top of the divide board a handle 24 is pivoted, as at 25, at a point between the ends of the said divide board. Thus the outer end of the divide board is supported 85 by the bearing plate 18 and fits in the opening 17 so that the side walls of the latter properly center the divide board. By the described arrangement of the divide board the same may be raised out of its normal position and thrown upward or lowered when required without the assistance of an extra man, which is necessary with the forms of 90 divide board generally employed.

My invention thus provides an efficient 100 bundle-supporter of simple and cheap construction, which may be applied to known makes of self feeders, and will afford a proper support for the bundles at the outer end of the self feeder, and at the same time 105 provision is made in connection with the bundle supporter for the novel support of the divide board.

Having thus described my invention, I claim as new, and desire to secure by Letters 110 Patent:

1. A bundle supporter adapted for attach-

- 2
- ment to the self feeders of threshing machines, comprising a transverse body adapted to range across the front of the self feeder in front of the usual conveyer of the thresher, 5 said bundle supporter having an upwardly flaring top, the body and top being returned in a forward direction at the sides, and provided with means for securing the attachment to the self feeder.
- 10 2. A bundle supporter adapted for attachment to the self feeders of threshing machines, comprising a transverse body adapted to range across the front of the self feeder in front of the usual conveyer of the 15 thresher, said bundle-supporter inclining outwardly and upwardly at the top and having an opening extending through the front and through the said inclined top for receiving a divide board, there being a rest 20 extending forwardly at the inner side of the bundle supporter at the lower end of the opening for supporting the divide board.
3. A bundle supporter adapted for attachment to the self feeders of threshing machines, comprising a transverse body adapted 25 to range across the front of the self feeder in front of the usual conveyer of the thresher, said bundle supporter being formed at the top to afford support for the 30 bundles, and means associated with the bundle-supporter to afford support for the front end of a divide board, the inner side of the supporter being downwardly and forwardly inclined at the sides of and below the said 35 means.
4. The herein described attachment adapted to be secured to the self feeders of threshing machines, comprising a body adapted to range across the self feeder in front of the usual conveyer of the thresher, the body being formed of sections and laterally adjustable, the top of the attachment inclining

upwardly and outwardly and the body of the attachment, as well as the said inclined top, being returned at the sides in a forward direction, means to secure the attachment at the front, there being an opening in the front and inclined top at the approximate center for the reception of the end of a divide board, and a forwardly extending rest for the divide board at the said opening.

5. A bundle supporter, adapted for attachment to the self-feeder of a threshing machine, said supporter being formed of slidably connected sections, the supporter furthermore having rearwardly returned end portions provided with attaching members adapted to be secured to the self-feeder of the thresher.

6. A bundle supporter adapted for attachment to the self-feeder of a threshing machine, comprising a transverse body formed of sheet metal having a front wall and an upper portion bent over rearwardly, the upper end of the front wall and the said bent portion being inclined to present a forward and upward flare.

7. A bundle supporter adapted for attachment to the self-feeder of a threshing machine, comprising a transverse body formed of sheet metal having a front wall and an upper portion bent over rearwardly, the upper end of the front wall and the said bent portion being inclined to present a forward and upward flare, there being means to receive a divide-board at the said flaring portion of the bundle supporter.

In testimony whereof I have signed my name to this specification in the presence of two subscribing witnesses.

PETER POWERS.
